UNITED STATES PATENT OFFICE

JAMES R. CLARK, OF ROCHESTER, NEW YORK, ASSIGNOR TO THE YAWMAN & ERBE MANUFACTURING COMPANY, OF NEW YORK, N. Y., A CORPORATION OF NEW YORK

YIELDING RETAINER FOR VISIBLE INDEX CARD HOLDERS

Application filed June 26, 1930. Serial No. 463,918.

This invention relates to an improved organization of elements for retaining yieldingly card holders within a tray while permitting their removal when required upon 5 operation of the parts. Generally speaking, the improved mechanism includes a retaining bar which is normally urged yieldingly against the ends of the card holders to prevent their displacement and an independent 10 pressure-relieving means which is operable manually to relieve the said retainer bar from the action of the yielding pressure elements, when the holders are to be removed. The construction is simple and compact and easy 15 to operate, the pressure-relieving means being movable positively to relieve the retaining bar of the spring action, and operable automatically to restore the spring action to the retaining bar when and as desired.

20 In accordance with the object of the invention a free retaining bar is mounted in cooperative relation to the card holders and is normally subjected through suitable interposed elements to the action of spring means.

25 To relieve the retaining bar of the spring action a manually operable spring-compressor is provided by means of which the spring pressure can be removed from the retaining bar, leaving the latter free for displacement, 30 as when the card holders are displaced for removal from the tray. In the preferred embodiment, the spring-compressor is free to return to release the springs when the manual pressure thereon is removed. Further, 35 it is preferred that the spring-compressor shall be operatively engaged with fixed means on the tray to bring about by a positive action compression of the springs.

40 These and other objects will appear at greater length hereinafter in connection with the description of the embodiment illustrated in the drawings, in which:

Figure 1 is a view in plan of a tray having the improved card-retaining mechanism associated therewith, a part of the tray being broken away to show such mechanism.

Figure 2 is a view similar to Figure 1 but on a somewhat larger scale showing the spring compressor in action, the retaining bar

for the card holders being left free for lateral movement.

Figure 3 is a view in transverse section through the tray shown in Figure 2 and taken on the plane indicated by the line 3-3 of Figure 2 and looking in the direction of the arrows.

Figure 4 is a sectional view of the finger pull for the spring compressor taken on the plane indicated by the line 4-4 of Figure 2 and looking in the direction of the arrows.

Figure 5 is a fragmentary sectional view showing the relation between the compressor bar and the fixed cooperating pins taken on the plane indicated by the line 5-5 of Figure 1.

Figure 6 is a view similar to Figure 5 but showing a section through the actuating mechanism taken on the plane indicated by the line 6-6 of Figure 1.

The tray *a* may be of any suitable form, that illustrated having channels at its opposite sides formed by reversely bent flanges *a*, *a*². Within the flange *a*' may be placed a bar or stop *b* to limit movement of the card holders *c* to the right as viewed in the drawings. The other end of the card holders lie in the other channel under the flange *a*². When the bars are to be removed from the tray it is contemplated that they shall be displaced towards the left, as viewed in the drawings, until their right-hand ends clear the flange *a*' at which time they may be withdrawn. To hold them against accidental movement when the tray is in use there is provided a retaining bar *d* which normally engages the left ends of the holders. This retaining bar is a free element being subject only to the action of suitable springs illustrated as leaf springs disposed within and bearing against the vertical member or bottom of the channel *a*². Interposed between the springs *e* and the retaining bar *d*

is a spring-compressor shown as comprising a longitudinally extending bar *f*. This bar may be recessed along its inner edge as at *f*' to receive the springs *e*. This bar can be manipulated to compress the springs *e* and thereby relieve the retaining bar *d* from their action.

In order that the spring-compressor *f* shall compress the springs *e* it is necessary that it be moved laterally against the springs, as shown by comparing Figures 1 and 2. It is desirable that this movement of the spring-compressing bar shall be brought about by positive cooperating elements. To this end the spring-compressor is formed with openings *f*², which are preferably of generally triangular outline. Through these openings extend pins *g* secured to the tray. A finger pull *h* extends through an opening *a*² in the flange *a*² and engages the compressor bar *f*. By grasping the finger pull *h* the bar *f* can thus be slid longitudinally. Such movement will bring the inclined sides of the triangular openings *f*² into cooperative engagement with their respective pins *g* so that camming ensues and the bar *f* will be constrained to move laterally against the action of the springs *e* thereby compressing them. With the parts in such condition the retainer bar *d* will be left wholly free and isolated from the spring action. If one or more of the card holders *c* are then slid laterally they will displace the retainer bar *d* laterally leaving the card holders free to be withdrawn from the tray. The pins *g* may extend through transverse openings *d*² in the retainer bar *d* to permit movement of this bar laterally without interference. At the same time, this slot and stud connection will permit the spring-compressing bar *f* to be moved longitudinally and laterally without impressing its movements on the retaining bar *d*. When the retaining bar is to resume its function of holding the card holders yieldingly against displacement, the finger is removed from the pull *h* thereby permitting the springs *e* to reassert themselves and move the compressor *f* along with the bar *d* towards the right as viewed in Figure 2.

Changes in mechanical details and the substitution of equivalents will suggest themselves to one skilled in the art and any such modifications are to be deemed within the scope of the invention defined by the appended claims.

What I claim is:

1. In combination with a tray having channels along its edges, rigid members mounted transversely of the tray within the channels, a retaining bar engaging the ends of the members to hold them against lateral displacement, resilient means for normally urging the bar yieldingly against said members, and means operatively interposed between said resilient means and said bar to transmit the pressure of said resilient means to the bar and operable to relieve the bar of the pressure of said resilient means.

2. In combination with a tray having channels along its opposite edges and members disposed transversely of the tray and engaged with said channels, a retaining bar

mounted in one of said channels and engaging the ends of said members, spring means to urge the bar yieldingly into engagement with said members and spring-compressing means operatively interposed between the springs and the bar and movable against the action of said springs to isolate the retaining bar from their pressure.

3. In combination with a visible index tray having channels along its side edges, rigid card holders mounted in the tray and engaging the channels, a retaining bar disposed in one of the channels and engaging the ends of said card holders, springs engaging the bottom of said last-named channel, a second bar mounted in the same channel between the retaining bar and the springs and adapted to be pressed by the latter yieldingly against the former, and means to move said second-named bar laterally away from the first-named bar by positive actuation against the pressure of said springs.

4. In combination with a visible index tray having channels along its side edges, rigid card holders mounted in the tray and engaging the channels, a retaining bar disposed in one of the channels and engaging the ends of said card holders, springs engaging the bottom of said last-named channel, a second bar mounted in the same channel between the retaining bar and the springs and adapted to be pressed by the latter yieldingly against the former, and means carried by the tray and operatively engaged by the second-named bar to move the same laterally upon longitudinal movement thereof to effect compression of the springs.

5. In combination with a visible index tray, rigid card holders disposed transversely thereof, a retaining bar therefor, springs, a spring-compressing bar operatively interposed between said springs and said retaining bar, and means to shift the compressing bar longitudinally and laterally to compress the springs and isolate the retaining bar from their pressure.

6. In combination with a visible index tray, rigid card holders disposed transversely thereof, a retaining bar therefor, springs, a spring-compressing bar operatively interposed between said springs and said retaining bar and shiftable longitudinally and laterally to compress the springs and isolate the retaining bar from their pressure, and pins carried by the tray and extending through openings in the compressor bar, said openings being of such configuration as to permit lateral displacement of the compressor bar in one position and cause positive lateral displacement thereof upon longitudinal movement of the same.

7. In combination with a visible index tray having channels along its side edges, card holders mounted in the channels, a retaining bar in one of the channels having a flange

to engage the ends of the holders and a web parallel to the floor of the tray, springs seating at the bottom of said channel and a compressor bar for the springs of generally rectangular cross-section nested within the L-shaped retaining bar and operatively interposed between said bar and said springs.

This specification signed this 24th day of June, A. D. 1930.
